CONVERTIBLE HEATING AND COOLING SYSTEM

Bo Folke Randel, San Diego, Calif.

Application February 10, 1936, Serial No. 63,172

1 Claim. (Cl. 257—9)

(Granted under the act of March 3, 1883, as amended April 30, 1928; 370 O. G. 757)

My invention relates to heating and cooling systems and it has for its principal object the provision of a system which is simple to operate and which may be alternately used for either heating or cooling by the manipulation of a few valves. The different parts of the system remain unchanged whether they function as heating means or as cooling means.

Another object of the invention is the provision of a chambered temperature control element in which heat is absorbed or given up, as desired, whereby the element is capable of functioning as a conventional heat radiator of a heating system or as a conventional evaporator of a refrigerating system.

When operating as a heating system, the element or elements will be supplied with a vaporized heating medium such as steam, which is condensed in the same to pass its latent heat to the portion to be heated. When operating as a cooling system, the cycle will be reversed in that a liquid refrigerant such as water will be supplied to the same element or elements, which now will act as evaporators and in which the refrigerant will be vaporized by the reduction of the pressure, thus absorbing heat from the surrounding environment.

The boiler, condenser, vacuum pump, ejector, etc., may be constructed in many different ways. Local control valves may be added as desired. Float valves, pressure reducing valves, safety devices, recording devices, thermostatic control devices may be added as desired.

With these and other objects in view, as well as other advantages which may be incident to the use of the improvements, the invention consists of the parts and combinations thereof hereinafter set forth and claimed with the understanding that the several necessary elements constituting the same may be varied in proportion and arrangement without departing from the nature and scope of the invention, as defined in the appended claim.

In order to make the invention more clearly understood, there are shown in the accompanying drawing means for carrying the invention into practical effect, without limiting the improvements in their useful application to the particular construction, which, for purposes of explanation, have been made the subject of illustration.

In the accompanying drawing:

Fig. 1 is a diagrammatic view showing my system, consisting of a boiler, a vacuum pump, a

condenser, ejectors and two different types of radiators;

Fig. 2 is a fragmentary vertical sectional view of a modified form of radiator element.

Referring to the drawing, and particularly to Fig. 1 thereof, the invention is shown as comprising a pair of convertible heat radiating and heat absorbing elements or units 10 and 11 communicating with a steam inlet header 12 through laterals 13 and 14 respectively, and with a condensate return header 15 through return laterals 16 and 17 respectively, the former including a trap 18 and valve 19, and the latter including a trap 20 and valve 21. The inlet header 12 communicates with a steam boiler 22, provided with a suitable source of heat 23, through a pipe 24 controlled by a valve 25. The return header 15 communicates through a pipe 26 and valve 27 with a chamber 28, which in turn communicates with a receiver or tank 29, containing a cooling coil 30 and partially filled with a liquid, through a pipe 31 provided with a Venturi tube 32. Reduced pressure is maintained within the chamber 28 by means of an ejector 33 through which liquid is projected at high velocity by means of a pump 34 which communicates with the tank 29 through a pipe 35 and which is driven by an electric motor 36. Water of condensation is returned to the boiler 22 through a pipe 37 communicating with the injector 33.

Water or other liquid refrigerant is supplied to the elements 10 and 11 through pipes 38 and 39 respectively, provided with float actuated check valves 40 and 41, the pipe 38 being additionally provided with a manually operable valve 42. The pipes 38 and 39 communicate at their lower ends with the laterals 13 and 17 respectively, which also communicate through return header 15 with a pipe 43 in turn communicating with the pipe 37 and controlled by a valve 44.

The system also includes ejector nozzles 45 and 46 for projecting a fluid at high velocity through Venturi tubes 47 and 48 provided in the laterals 13 and 14 respectively. These nozzles communicate with a high pressure main 49 through pipes 50 and 51 which in turn communicate with the boiler 22 through a pipe 52 and valve 53. The fluid projected through the Venturi tubes 47 and 48 during the cooling cycle and laterals 13 and 14 passes to the low pressure chamber 28 through the low pressure header 12 and a pipe 54 and valve 55. From the chamber 28 the fluid is returned to the boiler 22 through the Venturi tube 32, pipe 31, tank 29, pipe 35, pump 34, ejector 33, and pipe 37.

To better illustrate the operation of the system, arrows are employed to indicate the direction of flow of the liquids under different conditions. The arrows marked *h* indicate the direction of flow of the fluid when the system is employed for heating purposes, and the arrows marked *c* indicate the direction of flow of the fluids when the system is employed for cooling purposes.

When the system is operated as a heater the 10 valves 25 and 27 are opened and the valves 44, 53 and 55 are closed. Under these conditions steam generated in the boiler 22 passes through pipe 24 and valve 25 to the header 12 and thence through the laterals 13 and 14 to the radiators 15 10 and 11. The steam condensed in the radiators passes through the check valves 19 and 21 and traps 18 and 20 to the return laterals 16 and 17 and thence through the return header 15, and pipe 26 and valve 27 to the reduced pressure 20 chamber 28, the flow of the condensate being caused by the suction developed by the injector jet 33 and Venturi tube 32 and by the condensate being entrained by the fluid injected. From the chamber 28 the condensate passes through the 25 Venturi tube 32 and pipe 31 into the receiving tank 29, where it collects. The pump 34 draws the water from the tank 29 through pipe 35 and forces it through the rear end of the injector 33 and pipe 37 back to the boiler 22.

When the system is operated for cooling purposes the valves 44, 53 and 55 are opened and the valves 25 and 27 are closed. Under these conditions the flow of the cooling medium is practically reversed in that the water or other refrigerant 35 will pass upwardly under pressure through pipe 43 and valve 44 into the main 15 and thence upwardly through laterals 16 and 17, pipes 38 and 39, manually operable valve 42 and float valves 40 and 41 into the radiator elements 10 and 11. It will be noted that the pressure of the liquid refrigerant maintains the check valves 19 and 21 closed, and that the float valves 40 and 41 control the amount of refrigerant injected into the 45 elements 10 and 11 so as to maintain a desired liquid level.

Steam or vaporized refrigerating medium will also pass from the boiler 22 through the pipe 52 and valve 53 into the main 49 and thence through the pipes 58 and 51 to the injector nozzles 45 and 50 46 through which it is projected at high velocity into the Venturi tubes 47 and 48. The suction thus produced in the elements 10 and 11 causes the evaporation of the refrigerant therein and the resultant absorption of heat from the 55 surrounding environment. From the laterals 13 and 14 the steam flows into the low pressure header 12 and thence through the pipe 54 and valve 55 into the low pressure chamber 28 under the suction developed by the injector jet 33. At this point the 60 steam is entrained by the liquid projected by the injector and is carried thereby through the Venturi tube 32, and pipe 31 into the receiving tank 29, where it is cooled and condensed by the coil 38. The condensate then passes back to the boiler through the pipe 35, pump 34, injector 33 and pipe 37 as before.

The radiator element 10 embodies upper and lower headers 56 and 57 respectively, and connecting pipes 58 of conventional construction. The

element 11, however, is shown as comprising a plurality of superimposed spaced evaporating pans 59 communicating with one another through overflow pipes 60 and in which the liquid refrigerant flows downwardly. Both of the two types of radiators are suitable for either heating or cooling purposes.

In Fig. 2 there is illustrated still another form of radiator element. In this construction upper and lower headers 61 and 62 are connected by vertical pipes 63 provided with heat radiating fins 64. Pipes 65 of smaller diameter extend vertically through the pipes 63 in spaced relation therewith. The purpose of this arrangement is to cause circulation of the heating or cooling medium 15 between the headers 61 and 62, the medium between the pipe 63 and pipe 65 being relatively warm will flow upwardly, while the medium within the pipe 65 being relatively cold will flow downwardly when the system is employed for cooling 20 purposes. When the system is used as a heater the direction of flow of the medium through the pipes 63 and 65 will, of course, be the reverse.

Many other forms of apparatus may be employed. The liquid may be sprayed into the 25 evaporator or it may be allowed to fall in drops through the same. Also, other mediums may be employed as a refrigerant such as ammonia, hydrocarbons, sulphur dioxide, for example.

Other modifications and changes in the proportions and arrangement of the parts may be made by those skilled in the art without departing from the nature and scope of the invention, as defined in the appended claim.

The invention described herein may be manufactured and used by or for the Government of the United States of America for governmental purposes without the payment of any royalties thereon or therefor.

I claim:

In a convertible heating and cooling system, the combination of a chambered temperature controlling element; a boiler for supplying heated vapor under pressure; a source of liquid refrigerant; an ejector for reducing the pressure within said element; valve means for establishing communication between said element and said boiler when the system is employed for heating purposes, and for interrupting the aforesaid communication when the system is employed for cooling purposes; valve means for establishing communication between said element and said supply of refrigerant and also between said ejector and said boiler under pressure to accelerate the rate of evaporation of the refrigerant, when the system is employed for cooling purposes, a condenser communicating with said element and said boiler; and an injector for withdrawing liquid of condensation and vaporized refrigerant from said element and forcing the same into said condenser; and a pump for operating said injector and for withdrawing liquid refrigerant from said condenser and forcing the same into said element when the system is employed for cooling purposes and for withdrawing liquid from said condenser and forcing the same into said boiler when the system is employed for heating purposes.

BO FOLKE RANDEL.
